UNITED STATES PATENT OFFICE.

ELMER R. ROSS, OF BRIDGEPORT, CONNECTICUT, ASSIGNOR TO THE RAYBESTOS COMPANY, OF BRIDGEPORT, CONNECTICUT, A CORPORATION OF CONNECTICUT.

DETACHABLE EAR FOR TRANSMISSION BANDS.

Application filed September 4, 1924. Serial No. 735,901.

To all whom it may concern:

Be it known that I, ELMER R. Ross, a citizen of the United States, residing at Bridgeport, county of Fairfield, State of Connecticut, have invented a new and useful 5 Detachable Ear for Transmission Bands, of which the following is a specification.

My invention relates to transmission and 10 brake bands for automobiles and especially to a removable ear for the transmission bands of the Ford type of transmission.

It is well known that the Ford type of transmission comprises three rotating drums, one for the low speed, one for the reverse 15 and one for the brake located closely adjacent each other and enclosed in a casing including a cover comprising substantially the whole upper half of the casing, and which cover has a small opening in its top 20 over these drums closed by a hand plate. Each drum is substantially encircled by a flexible steel band lined with asbestos or other suitable material, and are provided at their ends with ears secured thereto. 25 These ears are forked to receive the operating rods which are connected to the familiar operating pedals for clamping the bands about the drums as is well known. It is obvious that after the mechanism has been 30 used for some time the fibre linings for the bands wear out and must be renewed. Owing to the peculiar construction of the transmission and the transmission cover, in order to replace any of the linings it is necessary to remove and replace the entire 35 transmission cover, an operation which requires considerable time and furthermore after removing the cover it is difficult to properly replace it.

40 In order to overcome these objections, bands have been constructed with removable ears so that after detaching one of the ears from the band it may be withdrawn, relined and then returned to its position in the 45 transmission through the hand hole in the cover without removing the cover.

It is an object of my present invention 50 to provide an improved band having a detachable ear so that the band can be removed and applied through the hand hole without removing the cover, and also to provide an improved means for detachably securing the ear to the band which will be simple in con-

struction, may be quickly and easily fastened and unfastened, and which will be securely fastened so that it will not work loose in operation. 55

With the foregoing and other objects in view I have devised the construction illustrated in the accompanying drawing forming a part of this specification, similar reference characters being employed throughout the various figures to indicate corresponding elements. 60

Fig. 1 is a side elevation of one end of 65 the band and a section through the other end, showing my improved means for detachably securing the ear to the band.

Fig. 2 is a top plan view of the left half 70 of Fig. 1.

Fig. 3 is an elevation looking from the right of Fig. 2, and

Fig. 4 is a transverse section on an enlarged scale substantially on line 4—4 of 75 Fig. 1.

In the drawings I have not illustrated the three drums or the enclosing casing as their construction and arrangement is well known. I have, therefore, illustrated merely the end of a band and a removable ear 80 and securing means constructed according to my invention. The flexible and resilient metal band is indicated at 10 lined with the usual asbestos or other suitable lining 11, which embraces the proper drum. Secured to the free ends of the band are the ears 12 and 13, either one or both of which may be removably secured to the band, and these ears are provided with the usual fork 14 in which the operating rod rests. Secured to 85 the band and extending radially thereof are one or more studs 15. In the drawing I have shown two although one may be used or more as desired, and the curved portion 16 of the ear is provided with suitable openings 17 to receive these studs. This portion of the ear is curved substantially the same as the curvature of the band and is provided with strengthening ribs 18 to strengthen the 90 connection between this portion and the 100 fork.

The curved portion 16 is also provided with an elongated opening 19 preferably between the studs 15 and the forked portion of the ear. Secured to the band and pivoted 105 so that it may be turned to different posi-

tions is an oblong shaped button 20. This button is of such a size as to pass through the elongated opening when turned to a position longitudinally of the ear, but is of a length greater than the width of the opening so that when turned to a position transversely of the opening, as shown in Figs. 2 and 4, it cannot pass through the opening but its opposite ends will overlie the body portion of the ear on opposite sides of the opening. I prefer to mount this button substantially as shown, which mounting comprises a pivot stud 21 riveted to the band as shown at 22, there being a shoulder 23 to engage the upper surface of the band. The body portion of the stud extends through the opening 19 and has a reduced portion 24 at the top thereof extending through the button and forming a pivot therefor. The upper end of this portion is enlarged as shown at 25 to retain the button on the stud. Improved means is provided for retaining this button in the transverse or holding position so that it will not work loose in operation, but still may be easily and quickly released or applied in removing or attaching the ear. The band 10 is slit on opposite sides of the pivot 21 as shown at 26, these slits being of sufficient length to allow the intermediate portion 27 of the band on which the pivot stud is mounted to have a certain amount of movement relative to the body of the band and in a direction radially thereof. This portion is forced inwardly a certain amount so that it tends to pull the bottom toward the body portion of the ear. On opposite sides of the elongated opening the ear is provided with ribs 28 tapered in opposite directions and with a recess 29 in substantially the centers thereof and opposite the center of the elongated opening. The height of these ribs and recesses are such that, when after the button has been inserted through the elongated opening it is turned to the transverse position, its opposite ends will ride up the inclined surfaces 30 against the spring action of the resilient portion 27 until they reach the recesses 29, and then the resilient portion 27 will seat them tightly in these recesses as indicated. This resilient portion as will be obvious coacts with these recesses to prevent the button accidentally turning to the releasing position in operation. It may, however, be turned against the action of the spring by a suitable tool, as a pair of pliers, to release the button, and then the ear may be lifted off the band by an outward movement radially thereof.

This securing means is a very simple one but will positively lock the ear to the band. The ear may be applied and removed by mere radial movement with relation to the band, and there is no sliding movement about the band required. This makes it

easy to remove and apply in the limited space available in the transmission casing.

Having thus set forth the nature of my invention what I claim is:

1. A transmission or brake band comprising a curved strip of flexible material, a stud projecting outwardly therefrom, an ear having an opening to receive said stud and an elongated opening, and a button pivoted to the band and adapted to pass through said elongated opening in one position and having an overhanging portion arranged to move to a position over the ear to secure it to the band when turned from alignment with the opening. 70 75 80

2. A transmission or brake band comprising a curved strip of resilient material, a stud projecting outwardly therefrom, an ear having an opening to receive said stud and an elongated opening, and a button pivoted to the band and adapted to pass through said elongated opening in one position but of greater length than the width of the opening to secure the ear to the band when turned to a position transversely of the opening, the band being slit on the opposite sides of said pivot to provide a resilient portion movable relative to the rest of the band and on which the button is mounted. 90 95 100

3. A transmission or brake band comprising a curved strip of resilient material, a stud projecting outwardly therefrom, an ear having an opening to receive said stud and an elongated opening, and a button pivoted to the band and adapted to pass through said elongated opening in one position but of greater length than the width of the opening to secure the ear to the band when turned to a position transversely of the opening, the ear being provided with recesses on opposite sides of the opening to receive said button when in securing position, and the band being slit on opposite sides of said pivot to provide a resilient portion movable relative to the rest of the band and on which the button is mounted. 105 110 115

4. A transmission or brake band comprising a curved strip of resilient material, a stud projecting outwardly therefrom, an ear having an opening to receive said stud and an elongated opening, and a button pivoted to the band and adapted to pass through said elongated opening in one position but of greater length than the width of the opening to secure the ear to the band when turned to a position transversely of the opening, outwardly projecting ribs on opposite sides of said opening and extending longitudinally thereof, said ribs being provided with recesses in the top thereof to receive said button when in securing position and having inclined walls on opposite sides thereof, and the band being slit on opposite sides of said pivot to 120 125 130

provide a resilient portion movable relative to the rest of the band and on which the button is mounted.

5. A transmission or brake band comprising a curved strip of resilient material, a stud projecting outwardly therefrom, an ear having an opening to receive said stud and an elongated opening, and a button pivoted to the band and adapted to pass through said elongated opening in one position but of greater length than the width of the opening to secure the ear to the band when turned to a position transversely to the opening, the ear being provided with recesses on opposite sides of the opening to receive said button when in securing position and also having inclined surfaces leading to said recesses, and the band being slit on opposite sides of said pivot to provide a resilient portion movable relative to the rest of the band and on which the button is mounted.

6. A transmission or brake band comprising a curved strip of resilient material, a stud projecting outwardly therefrom, an ear having an opening to receive said stud and an elongated opening, a pivoted button adapted to pass through said elongated opening in one position but of greater length than the width of the opening to securing the ear to the band when turned to a position transversely of the opening, a resilient support for the button, and means carried by the ear coacting with said resilient support to retain the button in holding position.

7. A transmission or brake band comprising a curved strip of resilient material, a stud projecting outwardly therefrom, an ear having an opening to receive said stud and an elongated opening, a pivoted button adapted to pass through said elongated opening in one position but of greater length than the width of the opening to secure the ear to the band when turned to a position transversely to the opening, said ear being provided with recesses to receive said button and inclined surfaces leading thereto, and a resilient support for the button tending to hold it in said recesses.

8. A transmission or brake band comprising a curved strip of resilient material, an ear having an elongated opening therein, and a button pivoted to the band and adapted to pass through said opening in one position but of greater length than the width of the opening to secure the ear to the band when turned to a position transversely of the opening, the band being slit on opposite sides of said pivot to provide a resilient portion movable relative to the rest of the band and on which the button is mounted.

9. A transmission or brake band comprising a curved strip of resilient material, an ear having an elongated opening therein,

and a button pivoted to the band and adapted to pass through said opening in one position but of greater length than the width of the opening to secure the ear to the band when turned to a position transversely of the opening, the ear being provided with recesses on opposite sides of the opening to receive said button when in securing position, and the band being slit on opposite sides of said pivot to provide a resilient portion movable relative to the rest of the band and on which the button is mounted.

10. A transmission or brake band comprising a curved strip of resilient material, an ear having an elongated opening therein, and a button pivoted to the band and adapted to pass through said opening in one position but of greater length than the width of the opening to secure the ear to the band when turned to a position transversely of the opening, the ear being provided with recesses on opposite sides of the opening to receive said button when in securing position and also having inclined surfaces leading to said recesses, and the band being slit on opposite sides of said pivot to provide a resilient portion movable relative to the rest of the band and on which the button is mounted.

11. A transmission or brake band comprising a curved strip of resilient material, an ear having an elongated opening therein, a pivoted button adapted to pass through said opening in one position but of greater length than the width of the opening to secure the ear to the band when turned to a position transversely of the opening, a resilient support for the button, and means carried by the ear coacting with said resilient support to retain the button in holding position.

12. A transmission or brake band comprising a curved strip of resilient material, an ear having an elongated opening therein, a pivoted button adapted to pass through said opening in one position but of greater length than the width of the opening to secure the ear to the band when turned to a position transversely of the opening, said ear being provided with recesses to receive said button and inclined surfaces leading thereto, and a resilient support for the button tending to hold it in said recesses.

13. A transmission or brake band comprising a curved strip of resilient material, an ear, means for securing the ear to the band requiring movement of the ear in the direction radially of the band only, a resiliently mounted means for locking the ear to the band, and means carried by the band coacting with said resilient means to retain said locking means in securing position.

14. A transmission or brake band com-

prising a curved strip of resilient material, an ear, coacting means carried by the ear and band to prevent relative sliding movement of the ear on the band but which will 5 allow radial movement thereof, releasable means for preventing said radial movement, a resilient mounting for said means, and means carried by the ear coacting with the resilient mounting to retain the releasable means in holding position.

15. A transmission or brake band comprising a curved strip of resilient material, an ear having an elongated opening, a pivoted button adapted to pass through said 15 opening in one position and having an overhanging portion movable to a position over the ear to secure it to the band, a resilient support for the button, and means carried 20 port to retain the button in holding position.

16. A transmission or brake band comprising a curved strip of resilient material, an ear having an elongated opening, said 25 ear and band having coacting means to prevent relative sliding movement of the ear on the band, a button pivoted to the band adapted to pass through said opening in one position and having an overhanging 30 portion movable to a position over the ear to secure it to the band, said band being slit on opposite sides of the pivot to pro-

vide a resilient portion movable relative to the rest of the band and on which the button is mounted and means carried by the 35 ear coacting with the resilient portion to retain the button in holding position.

17. A transmission or brake band comprising a curved strip of flexible material, an ear having an elongated opening, said 40 ear and band having coacting means to prevent relative sliding movement of the ear on the band, a stud projecting outwardly from the band, and a securing button pivoted to the stud adapted to pass through 45 the opening when in one position and provided with an overhanging portion movable to a position over the ear to prevent movement of the ear radially of the band.

18. A transmission or brake band comprising a curved strip of flexible material, an ear having an elongated opening, said 50 ear and band having coacting means to prevent relative sliding movement of the ear on the band, a stud projecting outwardly 55 from the band, and a movable catch mounted on the stud arranged to pass through the opening in one position and movable laterally to a position to engage the top of the ear to prevent movement of the ear 60 radially outward from the band.

In testimony whereof I affix my signature.

ELMER R. ROSS.
